UNITED STATES PATENT OFFICE.

JAMES L. COOPER, OF PULASKI, VIRGINIA.

BOILER COMPOUND.

No. 880,126.

Specification of Letters Patent.

Patented Feb. 25, 1908.

Application filed July 27, 1907. Serial No. 385,861.

To all whom it may concern:

Be it known that I, JAMES L. COOPER, a citizen of the United States, residing at Pulaski, in the county of Pulaski, State of Virginia, have invented certain new and useful Improvements in Boiler-Cleaning Compounds; and I do hereby declare the following to be a full, clear, and exact description of the invention, such as will enable others skilled in the art to which it appertains to make and use the same.

The present invention has reference to boiler-cleaning compounds, and it has for its object the production of a compound which may be easily introduced into the interior of a boiler for effectually removing scale from the metal without injuring the latter.

To this end the invention consists in the provision of a compound consisting of the fol-

lowing ingredients, which, when taken on a 20 50 gallon basis, are mixed together in substantially the proportions specified,—viz:—
cutch, 20 pounds; borax, 4 pounds; soda ash, 10 pounds; coal oil, 3 gallons; and oak-bark ooze, 3 gallons.

What is claimed is:—

A boiler-cleaning compound consisting of cutch, soda ash, borax, coal-oil, and oak-bark ooze.

In testimony whereof, I affix my signature, 30 in presence of two witnesses.

JAMES L. ^{his} COOPER.
